DESIGN FOR A TEXTILE FABRIC

John M. Balsam, Kennilworth, N. Y.

Application October 15, 1937, Serial No. 72,201

Term of patent 3½ years

To all whom it may concern:

Be it known that I, John M. Balsam, a citizen of the United States, residing at Kennilworth, county of Nassau, and State of New York, have invented a new, original, and ornamental Design for a Textile Fabric, of which the following is a specification, reference being had to the accompanying drawing, forming part thereof, wherein—

The figure is a plan view of a textile fabric showing my new design.

I claim:

The ornamental design for a textile fabric substantially as shown.

JOHN M. BALSAM.
